PURIFICATION OF NAPHTHENIC ACIDS

Frederick J. Ewing, Pasadena, Calif., assignor to
 Union Oil Company of California, Los Angeles,
 Calif., a corporation of California

No Drawing. Application August 12, 1933,
 Serial No. 684,929

15 Claims. (Cl. 260—108)

This invention relates to the purification of naphthenic acids. A primary object thereof is to present a simple and thoroughly satisfactory process for effecting the permanent removal of substantially all of the dark coloration and pungent odor which usually accompany these acids.

Naphthenic acids, such as might be obtained from the alkali waste arising during the refining of petroleum or shale oil fractions, constitute a complex mixture of acidic compounds containing principally carbon, hydrogen and oxygen. They range from comparatively low boiling liquids to compounds which are solid or semi-solid at ordinary temperatures. Their viscosity in most instances is directly proportional to the viscosity of the hydrocarbon fractions in which they were originally present. The acidic character of the naphthenic acids is believed to be due to the presence of one or more carboxyl (COOH) groups in association with the remainder of a molecule.

Naphthenic acids, as originally obtained from the alkaline refining wastes of various hydrocarbon fractions including those stated above, possess a dark red to black color and this color subsists whether or not the acids be substantially free from associated phenolic and hydrocarbon materials. When such acids are distilled, which may or may not be performed under reduced pressure, the overhead product is substantially colorless at first but it rapidly reverts to a dark amber or black color on standing, thereby rendering the acids unfit for use in many instances. Therefore, it is desirable to obtain colorless naphthenic acids which do not darken on standing even over a long prolonged period of time and which also possess a bland to sweet odor.

I have discovered that such a decolorization and deodorization may be brought about by contacting the naphthenic acids with non-volatile oxidizing agents. This treatment may be carried out with the acids in either the liquid or vapor phase although from an economical standpoint it is preferable to resort to the former which in its simplest exemplification consists in adding the oxidizing agent directly to the still charge either before or during distillation.

The non-volatile oxidizing agents which I propose to use in this invention are metallic oxides which are capable of being transformed to the naphthenate salt of the metal or else reduced to the metal itself, in which latter case the naphthenate salt may be formed as an intermediate product.

Practically all metallic oxides may be used for the decolorization and deodorization of the naphthenic acids. Typical examples thereof are: magnesium oxide, MgO , mercuric oxide, HgO , aluminum oxide Al_2O_3 and vanadium oxide V_2O_5 .

The following metallic oxides have been found to be especially suitable for use in this invention: cupric oxide, CuO , ferric oxide Fe_2O_3 , litharge Pb_2O_3 , manganese dioxide MnO_2 and chromic oxide, Cr_2O_3 . The naphthenate salts of these metals which may be reduced to the free metal itself are themselves capable of bringing about the desired color stability and deodorization. Thus cupric oxide or cupric naphthenate, when added to a naphthenic acid still charge have proved to be equally effective in the production of naphthenic acids of high color stability and bland odor.

The treatment as hereinafter more fully described, is carried out in the absence of any appreciable quantities of water and thereby avoids the emulsification difficulties which arise on purifying naphthenic acids with aqueous solutions of various reagents. Another one of the advantages inherent in the use of any or all of the previously mentioned metallic oxides resides in the fact that the naphthenate salts of the metals are quite readily soluble in the naphthenic acids at the temperatures prevailing during the purification process thereby providing an excellent contact between the refining agent and the product to be purified. These naphthenate salts are non-volatile and remain in the still together with small amounts of the free metal itself, after distillation has been completed. As the amount of the metallic oxide added is usually very small, these naphthenates may be discarded along with the dark colored viscous residue. Should it be deemed desirable to obtain the free naphthenic acids from the still residue, this may be accomplished by the addition of small amounts of an inorganic acid such as sulphuric acid.

The finished product, obtained according to my invention is substantially free from phenolic material which is believed to be due to the distillation in the presence of the oxidizing agent at elevated temperatures; however I do not wish to be limited by any such theory. It is a known fact however, that the absence of phenols in naphthenic acid mixtures accounts for high acid numbers such as those indicated in the specific examples hereinafter described.

In practice, the crude naphthenic acids which have been preferably freed from the major fraction of the phenolic material are distilled in the presence of a small amount of dry steam or hydrocarbon gas in order to eliminate the admixed asphaltic and carbonaceous material. The partially purified naphthenic acids are then redistilled in the presence of small amounts of a metallic oxide such as cupric oxide or any of the metallic oxides set out above or any of the metallic naphthenates which are capable of bringing about the desired result. While this preliminary distillation process in the presence of steam or

gas has been found to be helpful in a number of cases, especially in such cases where it is desirable to avoid the use of sub-atmospheric pressures, it is not considered to be essential in the obtainment of the final result.

Therefore, my invention resides in the process for deodorizing and decolorizing naphthenic acid which comprises treatment with metallic oxides during distillation whereby a finished product is obtained which possesses a stable water-white to straw color and a bland odor. My invention also extends to the distillation of naphthenic acids in the presence of cupric oxide or to distillation with a non-volatile oxidizing agent such as cupric naphthenate which will accomplish the purpose intended.

Considering the process in greater detail, a caustic liquor, such as might be obtained by treating crude kerosene or a liquid sulphur dioxide extract thereof, with sodium hydroxide, is neutralized in such a manner that it is only slightly basic toward phenolphthalein. By so operating, the naphthenic acids, in contrast to the phenols, are not liberated from their alkali metal salt but remain as sodium naphthenates. The resulting mixture of sodium naphthenates, phenols and admixed hydrocarbons is then steam distilled. The sodium naphthenates remain behind in the still and when dissolved in water and treated with sulphuric acid, produce naphthenic acids which contain only very small amounts of phenols and admixed hydrocarbons. These crude naphthenic acids are of a poor color and contain considerable amounts of insoluble carbonaceous material. They are preferably subjected to a preliminary distillation in the presence of dry steam or some of the normally gaseous hydrocarbons such as ethane or methane, to remove the above-mentioned undesirable fractions. The effect of the introduction of the steam or gas is to lower the temperature necessary to distill the mixture and thereby avoid any undue cracking and eliminates the necessity of carrying out the distillation under reduced pressure.

The overhead when first condensed is a clear light yellow liquid but acquires a deep red color so rapidly that in a few hours, layers greater than an inch in depth are virtually opaque. Small amounts of water usually come over during the initial stages of the distillation and may be removed by a simple settling or centrifuging process. The "semi-refined" naphthenic acids which were condensed as an overhead product are subsequently introduced into a still into which small amounts of the oxidizing agent, ranging from 1 to 6% by weight, have been placed. The mixture is then redistilled under atmospheric pressure until substantially all of the purified naphthenic acids are removed as an overhead product. The so obtained finished naphthenic acids are of excellent color, possess a bland to sweet odor and do not darken on standing even for a period as long as six months. In addition, they possess an increased acid number and saponification number and a decreased sulphur content in comparison with the crude product.

I may also introduce the metallic oxides or naphthenates into the still as the distillation progresses instead of adding them before the naphthenic acids are introduced as described above. Temperatures substantially in excess of 580° F. should be avoided during the distillation. Therefore, when some of the higher boiling viscous acids are to be purified by my invention, the distillation should be carried out under reduced pressure so as to avoid any substantial amount of decomposition.

The following example is illustrative of my process:

Example 1

A mixture of crude naphthenic acids derived from the caustic liquor obtained in the refining of a kerosene fraction and which has been substantially freed from admixed phenols by careful acidification, steam distillation and acidification of the sodium naphthenate residue as previously described, had the following properties:

Acid number	283 mgs. KOH per gram of substance	15
Saponification number	283 mgs. KOH per gram of substance	
Specific gravity	0.97	
Color	Dark brown	
Sulphur content	0.21%	20
Boiling range	480-580° F.	
Sediment	1 to 2%	

These acids were subsequently distilled in the presence of small amount of dry steam or hydrocarbon gas which was introduced into the still during the distillation. The semi-refined naphthenic acids which were condensed as an overhead product had the following properties:

Acid number	284 mgs. KOH per gram of substance	
Saponification number	286 mgs. KOH per gram of substance	
Specific gravity	0.95	35
Sulphur content	0.12%	
Boiling range	480-575° F.	
Sediment	None	40

The naphthenic acids condensed as an overhead product had a clear straw like color which deepened into a dark red after standing for only 4-5 hours.

Four hundred (400) cubic centimeters of these acids were introduced into a still to which four grams of cupric oxide had been added. The overhead fraction comprising the finished naphthenic acids had the following characteristics:

Acid number	295 mgs. KOH per gram of substance	
Saponification number	298 mgs. KOH per gram of substance	
Specific gravity	0.948	55
Sulphur content	0.08%	
Color	1 to 1½ N.P.A.	
Color of same material after standing for 6 months	1 to 1½ N.P.A.	60
Boiling point range	480-570° F.	
Odor	Bland	65

The still bottoms which consisted of a carbonaceous residue together with small amounts of metallic copper and copper naphthenates (both cuprous and cupric naphthenates) were discarded. A total amount of 380 cubic centimeters of purified naphthenic acids were obtained as an overhead product during the distillation. They had an excellent color which did not change on standing, 75

even for a period of six months as may be seen from the table.

Example 2

5 The same amount of naphthenic acids used in Example 1 was redistilled in the presence of 4 grams of cupric naphthenate. The finished product obtained on condensation of the naphthenic acid vapors had properties very analogous to the product obtained on distillation with cupric oxide as may be seen from the following table:

Acid number	296 mgs. KOH per gram of substance
Saponification number	301 mgs. KOH per gram of substance
15 Specific gravity	0.948
Sulphur content	0.10%
Color	1 to 1½ N. P. A.
20 Color after standing for 6 months	1 to 1½ N. P. A.
Boiling point range	480-570° F.
25 Odor	Bland

As a modification of the process described above, I may pass the vapors of the semi-refined naphthenic acids through a tower filled with clay or other adsorptive substance which has been impregnated with cupric oxide or cupric naphthenate or any other oxide or naphthenate which is capable of improving the color and odor of naphthenic acids. The adsorption tower should be 30 preferably equipped with a dephlegmator to throw down any metallic naphthenates or metallic oxide which might otherwise be carried over with the naphthenic acid vapors and contaminate the finished product. The adsorption tower should 35 preferably be equipped with means for introducing fresh reagent and for removing the waste products. A multiplicity of towers each filled with an adsorptive agent and using only one tower at any particular time has proved to be very 40 successful as one of the towers may be recharged while the others are being used.

I may also heat the above mentioned "semi-refined" naphthenic acids in a pressure vessel together with a small amount of the oxidizing agent which I propose to use. The heating is 45 continued at a temperature of about 450 to 550° F. under the pressure generated by the vaporization of the naphthenic acids for about one to two hours whereupon the vessel is cooled and any 50 prevailing pressure released as soon as room temperature has been reached. Mechanical agitators placed within the pressure vessel are found to be very effective in obtaining a more efficient contact between the naphthenic acids and the oxidizing agent during heating. The cooled liquid 55 naphthenic acids together with small amounts of metallic naphthenates dissolved therein, are decanted and treated with a sufficient amount of sulphuric acid to liberate the free naphthenic acids from the naphthenate salts. The acid reaction products are removed by settling or centrifuging from the supernatant naphthenic acids. The latter are preferably distilled to remove any 60 dissolved impurities and the naphthenic acids, condensed overhead, constitute the finished product and possess the desired color stability and a bland odor as previously described.

Although the above mentioned process has been more particularly described in connection with naphthenic acids derived from kerosene, it may

be equally well carried out in the purification of higher boiling naphthenic acids derived from heavier hydrocarbon fractions such as stove oil or lubricating oils.

It is to be noted that, the naphthenic salts referred to above need not necessarily be derived from the oxides of the metals. Thus, where it is desirable to purify naphthenic acids with copper naphthenates, I may add cupric carbonate to the naphthenic acid still charge and produce my cupric naphthenate by the action of the naphthenic acids on this reagent. However, I prefer to use cupric oxide as this compound itself is capable of decolorizing and deodorizing the naphthenic acids.

The term N. P. A. color referred to in this specification relates to a color grade of a liquid obtained by means of the Union Petroleum Company colorimeter adapted as a standard by the National Petroleum Association in 1915. A detailed description of the apparatus, method of test and significance of the scale readings is found in David T. Day, Handbook of Petroleum Industry, 1922, vol. 1, page 665. For example, N. P. A. 0.5 indicates a light, almost white color, 25 N. P. A. 3 a yellow to straw color and N. P. A. 7 or 8 a dark reddish to brown color.

This invention is not restricted to any specific example described therein, the examples being merely illustrative of the generic invention herein disclosed and many variations may be made within the scope of the appended claims.

I claim:

1. A process for deodorizing and decolorizing naphthenic acids which comprises distilling a mixture of crude naphthenic acids to remove the admixed carbonaceous materials present therein and redistilling the overhead product in the presence of a metal oxide whereby there is imparted a light color of high stability and a bland odor to the aforesaid naphthenic acids.

2. A process for deodorizing and decolorizing naphthenic acids according to claim 1 in which the metal oxide used is copper oxide.

3. A process for deodorizing and decolorizing naphthenic acids which comprises distilling a mixture of crude naphthenic acids to remove the admixed carbonaceous materials present therein and redistilling the overhead product in the presence of a metal naphthenate whereby there is imparted a light color of high stability and a bland odor to the aforesaid naphthenic acids.

4. A process for deodorizing and decolorizing naphthenic acids according to claim 3 in which the metal naphthenate used is copper naphthenate.

5. A process for deodorizing and decolorizing naphthenic acids which comprises extracting a petroleum fraction with alkali, neutralizing the resulting extract to liberate the phenols from their alkaline salts without attacking the alkali naphthenates, distilling the phenols overhead, liberating the free crude naphthenic acids from the alkali naphthenates remaining in the still after the said distillation for the removal of phenols has been completed, distilling the said free crude naphthenic acids to remove the admixed carbonaceous materials present therein and redistilling the overhead product in the presence of a metal oxide whereby there is imparted a light color of high stability and a bland odor to the aforesaid naphthenic acids.

6. A process for deodorizing and decolorizing naphthenic acids according to claim 5 in which the metal oxide used is cupric oxide.

7. A process for deodorizing and decolorizing naphthenic acids which comprises extracting a petroleum fraction with alkali, neutralizing the resulting extract to liberate the phenols from their alkaline salts without attacking the alkali naphthenates, distilling the phenols overhead, liberating the free crude naphthenic acids from the alkali naphthenates remaining in the still after the said distillation for the removal of phenols 5 has been completed, distilling the said free crude naphthenic acids to remove the admixed carbonaceous materials present therein and redistilling the overhead product in the presence of a metal naphthenate whereby there is imparted a light 10 color of high stability and a bland odor to the aforesaid naphthenic acids.
8. A process for deodorizing and decolorizing naphthenic acids according to claim 7 in which the metal naphthenate used is copper naphthen- 15 ate.
9. As a new and useful composition of matter, naphthenic acids which do not exhibit any tendency to discolor on standing and which are substantially free from phenolic material and having 20 a boiling point in excess of 480° F.
10. As a new and useful composition of matter, naphthenic acids of a bland odor which do not exhibit any tendency to become discolored on standing and which have an acid number greater 25 than 250 mgs. KOH per gram of substance and having a boiling point in excess of 480° F.

11. As a new and useful composition of matter, naphthenic acids of a bland odor which do not exhibit any tendency to become discolored on standing and which have an acid number of 295 mgs. KOH per gram of substance or better 5 and having a boiling point in excess of 480° F.

12. As a new and useful composition of matter, naphthenic acids of a bland odor having a permanent color of 1 to 1½ N. P. A. and having a boiling point in excess of 480° F. 10

13. As a new and useful composition of matter, naphthenic acids which do not exhibit any tendency to discolor on standing and substantially free from carbonaceous materials and having a boiling point ranging from approximately 480° F. 15 to 570° F.

14. As a new and useful composition of matter, naphthenic acids of a bland odor, which do not exhibit any tendency to become discolored on standing and which have an acid number in excess 20 of 250 mgs. KOH per gram of acid and a boiling point ranging from approximately 480° F. to 570° F.

15. As a new and useful composition of matter, naphthenic acids of a bland odor, which do not 25 exhibit any tendency to become discolored on standing and which have an acid number of 295 mgs. KOH per gram of acid or better, and a boiling point ranging from approximately 480° to 570° F. 30

FREDERICK J. EWING.
